ELECTRIC CLOCK MECHANISM

John W. Hobbs, Chicago, Ill., assignor to The
 George W. Borg Corporation, Chicago, Ill., a
 corporation of Delaware

Application March 2, 1936, Serial No. 66,532

4 Claims. (Cl. 185—11)

The present invention relates in general to a clock mechanism of the type adapted for use in connection with a vehicle, such as an automobile, and is more particularly concerned with an improved electrically actuated winding mechanism, whereby the clock will be automatically wound.

It is a primary object of the present invention to provide an improved automatic winding mechanism for a spring driven clock.

Another object is the provision of an electrically actuated winding mechanism for a clock, which is automatically deenergized when the clock is wound and energized when the clock approaches a run down condition.

A further object of the invention is the provision, in a clock of the character described, of protective means for preventing overheating and possible damage of the winding mechanism, due to abnormal energization thereof.

It is also an object of this invention to provide a protective device which will automatically disconnect the winding mechanism relative to the electrical source when abnormal heating occurs, and which will also operate to automatically re-connect the electrical supply as soon as the winding mechanism has cooled to a safe operating temperature.

A still further object resides in the provision of novel means whereby actuation of the timing mechanism will be continued without interruption during the interval in which the winding mechanism is being rewound.

In accordance with the general features of the preferred form of the invention, it is proposed to provide a conventional timing mechanism having a main driving gear which is retained against reverse movement by means of a detent pawl. The main driving gear is actuated in a forward direction by means of spring pressed pawls carried by an armature, this armature being mounted for rotative movement in one direction by means of an electro-magnet, and in the other direction by means of a spring which opposes the attraction of the armature by the magnet. It will be obvious that the spring will normally tend to actuate the driving gear in a forward direction and that for rewinding the clock, energization of the magnet will move the armature to a new position, thereby again tensioning the actuating driving spring.

The rewinding is accomplished automatically by means of a switch which is actuated in response to the movement of the armature, so that as the armature reaches a run-down position, the switch is closed to energize the electro-magnet

and return the armature to a position wherein the driving spring is again stressed. At this position, the movement of the armature operates to open the switch and demagnetize the electro-magnet.

The automatic winding device is arranged to operate from the storage battery of the automobile, and it has been found that when the battery is low or during starting of the car, particularly in the winter time, there is insufficient voltage to energize the electro-magnet sufficiently to move the armature and open the deenergizing switch in circuit with the electro-magnet winding. Under these conditions, the electro-magnet is energized for an abnormal period of time, with the result that the coil of the electro-magnet becomes overheated and there is a possibility of its being burned out or otherwise damaged.

To overcome this condition and protect the coil, it is proposed as an additional feature of the invention to provide a thermostatic switch, which will open the electro-magnet winding circuit when abnormal energization of the electro-magnet occurs. This switch consists of a bimetallic strip which, due to the flow of current for an abnormal period, will be flexed away from an associated contact and open the circuit. After a brief interval of approximately one minute, the bimetallic strip will have cooled sufficiently to re-establish the connection to the electro-magnet, whereby the armature will again be attracted to restress the spring. As soon as normal operating conditions are established with normal battery voltage, the thermostatic switch will remain closed and the switch which is actuated in response to the movement of the armature will again function to automatically energize and deenergize the electro-magnet and keep the main operating spring stressed at all times.

In order to prevent the clock from stopping during the rewinding or restressing of the main driving spring, a novel secondary or supplemental drive is provided. For this purpose, a spring connection is provided between the main driving gear and the driving shaft, the main gear being mounted for relative movement on the shaft. This spring is stressed during the time when the clock is being driven by the main driving spring and will continue the drive of the clock for a brief interval, during which time the electromagnet may act on the armature to again rewind or stress the main driving spring. The operation of the foregoing features will be more apparent from the following description.

Other objects and features of the invention will

more fully appear from the following detailed description, taken in connection with the accompanying drawings which illustrate a preferred embodiment thereof, and in which:

5 Figure 1 is a side elevational view of a clock embodying the features of the present invention;

Figure 2 is a transverse sectional view showing the winding mechanism in wound position, taken substantially on the line II—II of Figure 1;

10 Figure 3 is a similar view showing the winding mechanism at substantially the run-down position;

Figure 4 is a transverse sectional view showing details of the control switch and protective thermostatic switch for the electro-magnet of the winding mechanism, taken substantially on the line IV—IV of Figure 1;

15 Figure 5 is an elevational view showing the details of the electro-magnet and the thermostatic protective switch, when viewed from line V—V of Figure 4; and

Figure 6 is a detail view in section showing the operative relationship between the parts of the secondary driving mechanism, taken substantially on the line VI—VI of Figure 1.

20 As shown on the drawings:

Figure 1 of the drawings illustrates a clock which embodies the features of the present invention. This clock is composed of a timing mechanism, generally indicated at A, having a conventional escapement, gear train, hands and dial; and power means, generally indicated at B, including a main driving spring and an electrical rewind for intermittently stressing the main driving

25 spring.

The timing mechanism includes a main shaft 10 for driving the minute hand, this shaft having secured thereto for rotation therewith a pinion 11 which, through the usual train of gears, drives the hour hand of the clock. A hub 12 is rotatably mounted on the shaft 10 and carries at one end a gear 13 which drives the escapement mechanism. This end of the hub is connected to a spring 14, which spring is rotatable with the pinion 11 and frictionally engages the side face of the gear 13, thus enabling movement of the hands for setting the clock independently of the driving mechanism.

30 The opposite end of the hub 12 is formed with a peripheral flange 12a which cooperates with a centrally disposed extension 12b of the hub to define an annular groove 13a. A main driving gear 15 is rotatably supported on the extension 12b and is held in abutment with the outer edge of the flange 12a by a washer 13b over which the end of the extension is turned back as shown at 14a, sufficient clearance being maintained to permit rotation of the gear 15 on the extension.

35 It will be apparent that the hub 12, gear 13, and gear 15 provide a unitary assembly on the shaft 10, which is frictionally connected with the pinion through the spring 14. The hub 12 is retained against movement axially of the shaft 10, away from spring 14, by means of a collar 14b on the shaft, this collar forming an abutment for an internal shoulder 15a of the hub bore.

40 Movement of the gear 15 relative to the hub is limited by a projecting stud 15b on the gear 15, which is movable between the ends of an opening 15c in the peripheral flange 12a of the hub.

The gear 15 is connected to the hub through a spring 16 disposed in the groove 13a, one end of this spring being anchored in the gear 15 and the other end in the hub. With the foregoing arrangement, a secondary drive for the clock is

provided, which prevents a cessation or stopping of the timing mechanism during the interval when the main driving spring is being stressed or rewound.

45 As shown in Figure 6, it will be evident that movement of the gear 15 in a forward direction to the limit of its movement will stress the spring 16 in such a manner as to drive the hub 12 for a short interval of time.

50 There is also rotatably supported on the shaft 10 for independent movement at one end of the hub an armature 17. This armature comprises oppositely extending arm portions 18 and 19 which are deflected at their ends to form right angularly disposed projections 20 and 21 which define pole pieces cooperatively associated with the respective poles 22 and 23 of an electro-magnet.

55 Each arm of the armature carries a pivotally mounted pawl 24 having teeth at its free end for engagement with the teeth of the main driving gear 15. The pawl 24 is resiliently moved into engagement with the gear 15 by means of a spring 25 having one end in engagement with the pawl and its other end engaging a stop pin 26. The pawls 24—24 permit free movement of the armature in a counter-clockwise direction relative to the gear 15, but on movement of the armature in a clockwise direction, the armature and gear 15 will move as a unit. Movement of the gear 15 in a counter-clockwise direction, when the armature is being moved in a counter-clockwise direction, is prevented by means of a detent pawl 27. The pawl 27, however, will permit free clockwise movement of the gear 15.

60 Movement of the armature in a clockwise direction to actuate the timing mechanism is accomplished by means of a spring 28 having one end anchored, as at 29, to the armature, and its other end anchored, as at 30, to a bracket member 31 which is fixedly supported on the clock framework.

65 With the foregoing arrangement, it will be seen that when the armature is rotated in a counter-clockwise direction, the spring 28 will be tensioned and the energy stored in this spring may be utilized to drive the clock mechanism for a limited interval of time. Movement of the armature in a counter-clockwise direction is accomplished by energizing the electro-magnet of the winding mechanism.

70 The electro-magnet is supported on a back plate 32 of the frame structure by means of small projections 33 on the pole pieces 22 and 23, respectively, these projections extending through suitable openings in the back plate and being peened over.

75 Referring to Figure 1, it will be noted that the core of the electro-magnet comprises a plurality of iron laminations 34 having their ends extending into openings 35 in the faces of the poles 22 and 23 of the electro-magnet. Surrounding the core of the magnet is a coil winding 36 which in this instance is designed to operate on from 3.2 to 20 volts.

80 By energizing this coil from a suitable source, such as a storage battery, the poles 22 and 23 of the electro-magnet will be magnetized and attract the armature so that it will move in a counter-clockwise direction and stress the spring 28. It will therefore be evident that by intermittently energizing and deenergizing the electro-magnet, the spring 28 may be kept in a stressed condition and continue to drive the timing mech-

anism without any attention from the operator of the automobile.

It will be apparent that when the armature is moved in a counter-clockwise direction, the force of the main driving spring 28 becomes ineffective to drive the timing mechanism. It is during this interval that the secondary drive, by means of the spring 16 comes into play and drives the timing mechanism as previously described for a short interval, this interval being sufficiently long to permit tensioning of the spring 28 by movement of the armature, after which the main driving spring again drives the timing mechanism. The spring 16 will be reenergized by movement of the armature in driving the timing mechanism.

Intermittent energization and deenergization of the coil winding of the electro-magnet is accomplished by a switch which is actuated in response to the movement of the armature. This switch comprises a pivotally mounted arm 37 which is supported for rotational movement on an intermediate pivot 38. This pivot is supported on a bracket 39 which is secured to the back plate 32. One end of the switch arm 37 is provided with a contact 40 which is arranged to engage with a contact 41 to open and close the circuit to the coil winding of the electro-magnet. The contact 41 is secured to the outer end of a metallic strip 42, having its other end insulatingly anchored at 43 to the supporting bracket 39.

Snap action of the switch is accomplished by moving it past a dead center position. The opposite end of the arm 37 from the contact 40 is provided with a V-shaped notch 44 for receiving the notched end of a link 45, the other end of this link being also notched, as shown at 46, to receive therein the free end of a spring member 47 which is anchored at its other end, as shown at 48, to the bracket 39. The bracket 39 also carries a stop member 49 for limiting movement of the arm 37 of the switch away from the stationary contact assembly.

It will be observed that as the switch arm 37 and link 45 are brought into alignment by movement of the switch arm, the spring 47 will be stressed. Further movement of the switch arm will cause the spring 47 and link 45 to pass the dead center position, and the spring 47 will force the contacts 40 and 41 to be engaged or disengaged with a snap action.

Opening and closing of the switch is accomplished in response to movement of the armature by providing an angularly projecting arm portion 50 which is integrally formed with the switch arm 37, this projecting arm portion at its outer end being formed to define angularly disposed arms 51 and 52 which are so disposed as to be engageable by a pin 53 on the armature.

It will be observed that when the contacts 40 and 41 are in separated position, when the switch is open, the arm 51 is so disposed as to be engageable by the pin 53 when the armature is moved in a clockwise direction and nears the limit of its movement, at which time it is desirable to rewind the driving mechanism. Movement of the switch to closed position will act to bring the arm 52 into the path of travel of the pin 53, so that when the armature is moved in a counter clockwise direction by virtue of the electro-magnet being energized, the switch will again be opened to deenergize the electro-magnet coil winding as the armature comes to its limit of movement in a counter-clockwise direction. It will therefore be evident that with this arrange-

ment the driving mechanism is automatically and intermittently wound.

In the operation of the clock mechanism thus far described, it has been found that with a low battery or when cranking a car in the winter time, there is insufficient voltage to sufficiently energize the electro-magnet to move the armature in a counter-clockwise direction to the full limit of its movement in a counter-clockwise direction. In other words, instead of a full movement of the armature, the movement is only a partial movement, and while this movement will stress the main driving spring 28 a sufficient amount to continue the operation of the timing mechanism, the partial movement is not sufficient to cause an opening of the contacts 40 and 41 to deenergize the electro-magnet coil. Under these conditions, the electro-magnet will in a short time become overheated and may burn out or otherwise be damaged. In order to overcome this condition, an additional protective switch is provided in the energizing circuit of the electro-magnet coil.

This switch comprises a U-shaped strip of bimetallic metal 54 having one leg anchored, as shown at 55, to form an electrical connection or terminal and secure the bimetallic strip to a base 56 of suitable insulation material. The free end of the strip of bimetallic material is associated with the free end of a contact member 57 which is anchored at its other end to the insulation base and forms a terminal 58. It will thus be evident that the bimetallic strip and contact element 57 are in the circuit and carry current. The flow of abnormal current through the bimetallic strip will cause the free end portion of the strip to be flexed away from the contact element 57 and thus open the circuit. Snap-action of the contact members in opening and closing the circuit is accomplished by providing a spring member 59 having one end anchored to the insulation base and its other end deflected as shown at 60 to form a V which overlies the end of the bimetallic strip when the bimetallic strip is in contact with the contact element 57 and serves to delay the opening of the contacts until the forces deflecting the bimetallic strip are sufficient to overcome the action of the springs 59, whereupon the bimetallic strips snaps past the deflected end of the spring 59. Return of the bimetallic strip to a position in contact with the contact element 57 is likewise delayed by the deflected end of the spring 59 until sufficient force has been built up to overcome the action of the spring 59, whereupon the bimetallic strip snaps past the deflected end of the spring 59 and engages the contact element 57 positively. In operation, the thermostatic switch will heat up and open its contact in about twenty seconds, and will close its contact, upon cooling of the bimetallic strip, in about one minute. In other words, the thermostatic switch provides a relatively quick opening and delayed closing of its contacts.

The thermostatic switch intermittently energizes and deenergizes the electro-magnet coil under abnormal conditions in such a manner that the coil is not overheated and there is no possibility of damage. As soon as normal conditions of excitation are established, the thermostatic switch will remain closed, and the automatic operation will then be by means of the switch which is opened and closed in response to the movement of the armature.

The electrical connections to the clock are 75

shown schematically in Figure 1. A storage battery or other source of power is indicated at 61. As in the usual installation in automobiles, one side of the battery is grounded at 62 and the other side is connected through a conductor 63 to a terminal 64 on the back plate, this terminal being insulated from the back plate of the clock. A second terminal 65 is also provided and is grounded, as at 66, to complete the connection to the battery.

The energizing circuit of the electro-magnet coil is from the terminal 64 through a conductor 66^a to the terminal 58 of the contact element 57, through the thermostatic strip 54 to the terminal 55, the conductor 66^b to one end of the coil 36, from the other end of the coil, through the conductor 67 to the contact strip 42, contacts 41 and 40, the contact arm 37, through the pivot 38 or link 45 and the spring 47 to the bracket 39, hence to the back plate 32 and terminal 65.

From the foregoing description, it will be apparent that the present invention provides an improved electrically actuated winding mechanism, whereby a clock of the spring driven type may be automatically wound; wherein the winding of the clock is entirely automatic; an electric clock in which the electrical mechanism is protected against overheating and possible damage; and in which novel secondary power means are provided for driving the timing mechanism for a short interval during which the main driving mechanism is being energized.

It is of course to be understood that although I have described in detail the preferred embodiment of my invention, the invention is not to be thus limited, but only insofar as defined by the scope and spirit of the appended claims.

I claim as my invention:

1. A clock comprising a rotatable drive shaft, a first member for driving the shaft, a second member rotatably mounted on the first member, said members being connected for limited relative rotational movement, whereby the second member may drive the first member when the second member is rotated in one direction, a secondary spring connecting the members for rotating the first member when the second member is maintained stationary, means preventing rotation of the second member in the opposite direction, a main spring arranged for rotating the

second member in the first direction, and means for intermittently energizing the main spring.

2. A clock comprising a rotatable drive shaft, a first gear having a hub in driving connection with said shaft, a main driving gear rotatably mounted for limited relative rotational movement on said hub, whereby the main driving gear may drive the first gear when the main driving gear is rotated in one direction, a secondary spring connecting said gears for rotating the first gear when the main driving gear is maintained stationary, means preventing rotation of the main driving gear in the opposite direction, a main spring for rotating the main driving gear in the first direction, and means for intermittently energizing the main spring.

3. A clock comprising a rotatable shaft, a first gear rotatable on said shaft, a friction connection between said gear and shaft, a second gear having a limited relative movement connection with the first gear, whereby said second gear may drive the first gear after limited movement in one direction, a secondary spring connecting said gears for rotating the first gear when the second gear is maintained stationary, means preventing rotation of the second gear in the opposite direction, means including a main driving spring for rotating the second gear in the first direction, means for intermittently energizing the main spring, an escapement mechanism driven from the first gear, and a time indicating member driven from said shaft.

4. An electric clock comprising a frame structure, a driving mechanism including a winding magnet having a coil adapted to be energized from an electric circuit, and a thermostatic switch for opening and closing the circuit to said coil with a snap action in response to an overload current for a relatively short interval of time or a normal current for a relatively long period of time, said switch comprising a U-shaped thermostatic strip disposed in close proximity to said coil and anchored at one end, the other end being free for deflection, a fixed contact member having one end disposed for normal engagement by said free end, and a spring member delaying movement of the free end out of and into engagement with said contact, said contact and thermostatic strip being connected in said electric circuit.

JOHN W. HOBBS. 50
